SELF-ALIGNING COUNTER STOOL

Nils Herman Cederquist, Los Angeles, Calif.

Application March 5, 1938, Serial No. 194,086

3 Claims. (Cl. 155—95)

This invention relates to a self-aligning counter stool and to a connection between the seat and the pedestal of counter stools so as to make the seat self-aligning with respect to the counter when the seat is released.

In various circumstances, where seats are arranged on pedestals in a row before a counter, such as for example in soda fountains, it is highly desirable to have the seats self-returning to a predetermined normal position with respect to the counter. In this way the customer, after having been served on arising and releasing the seat, permits the seat to return to the normal position so that all empty seats will be aligned automatically either straightforwardly before the counter or at a predetermined angle with respect to the counter. The unoccupied seats thus arranged present a neat and attractive appearance.

It is an object of the present invention to provide an improved construction rendering the seats automatically returnable to a predetermined normal position which is of relatively simple and durable construction and which provides means for creating a partial vacuum in the construction when the seat is turned from the normal position. This partial vacuum is utilized to assist in returning the seat to its normal position.

Another object of the invention is to provide a self-aligning counter stool construction which is so designed as to efficiently and adequately keep all parts lubricated. Not only are the parts adequately lubricated so as to prevent wear and objectionable noise but the construction is so arranged that there is no possibility of lubricant escaping from the construction to soil the clothes of customers.

With the foregoing and other objects in view, which will be made manifest in the following detailed description and specifically pointed out in the appended claims, reference is had to the accompanying drawing for an illustrative embodiment of the invention, wherein:

Figure 1 is a view in side elevation of a counter stool illustrating the invention as having been incorporated therein;

Fig. 2 is a vertical section through the counter stool connection that connects the seat to the pedestal;

Fig. 3 is a bottom plan view of the tripod that is attached to the seat and which carries the pin, and of the socket for the pin; and

Fig. 4 is a view similar to Fig. 2 on a somewhat smaller scale illustrating the parts in the

position assumed when the seat has been turned from its normal position.

Referring to the accompanying drawing wherein similar reference characters designate similar parts throughout, the conventional counter stool consists of a suitable pedestal 10 which may be permanently secured to the floor such as by screws 11. These pedestals are usually made hollow so as to save in weight and in material. Supported on the conventional pedestal is a seat 12 having a suitable back 13.

The invention comprises a socket member 14 which is cylindrical in form or otherwise shaped to fit inside of the hollow top of the pedestal 10. This socket member carries at its top an outwardly extending flange 15 that extends outwardly over the top of the pedestal. One or more spacers 16 may be positioned on top of the pedestal beneath the flange so as to adjust the position of the socket with respect to the top of the pedestal and consequently adjust the elevation of seat 12 with respect to the floor. The flange 15 carries a pair of opposed shoulders 17 and 18 arranged at the opposite ends of the arcuate edge 19 of the flange. These shoulders constitute stops engageable by lug 20 on the tripod hereafter to be described. The socket 14 has a vertical central cylindrical bore 21 formed therein, the bottom of which terminates on an inclined surface 22. In the preferred form of construction the socket member is made of a single casting and the bore 21 is cored therein with its bottom enlarged as at 23 to form a clearance. The bore is then reamed down to the enlargement or clearance 23. The lugs 17 and 18 on the flange 15 are arranged so as to be transverse with respect to the direction of inclination of the inclined surface 22.

The socket member is held in any rotatably adjusted position by means of a suitable set screw 24 which is threaded into the pedestal. Thus, on loosening the set screw the socket member may be adjusted so that its inclined surface 22 will be directed downwardly and forwardly toward the counter and lugs 17 and 18 will be arranged in a line parallel to the counter. If desired, the inclined surface 22 and lugs 17 and 18 may be adjusted so as to be arranged at an angle to the counter. The seat 12 is supported by means of a tripod having arms 25 one of which carries the lug 20 which extends downwardly between the stops 17 and 18. Screws or similar fastening devices may pass through ap-

526 in the ends of the arms and into the bottom of the seat.

The tripod has a pin 27 arranged centrally thereof which has a beveled lower end as at 528 complementary to the inclined surface 22. This pin is machined to closely fit the interior of the socket member except for a horizontal encircling groove 29 formed thereon, a short distance above the lower end and above the top 10 of the enlargement 23. This groove constitutes a lubricant-receiving groove and is designed to receive either a heavy oil or a grease.

The operation and advantages of the improved construction are as follows: When the seat 12 is in its predetermined normal position, as shown on Fig. 2, the beveled lower end 28 on the pin rests flatly against the inclined surface 22 in the socket. When the seat is turned however rotation of the pin 27 causes its beveled lower end 20 to turn on the inclined surface 22 so that a type of cam action is produced which elevates the seat slightly, compare Figs. 2 and 4. This causes the space between the two surfaces 22 and 28 to 25 open with the result that a partial vacuum is formed in the bottom of the socket 14. This partial vacuum is maintained by the lubricant seal formed between the lubricant in groove 29 and the walls of the bore 21.

While the weight of the seat has some effect 30 in tending to cause it to automatically return to its predetermined normal position the creation of this partial vacuum is of material assistance. Usually the weight of the seat and back is relatively small constituting only a few pounds. By 35 the creation of the partial vacuum the effective weight tending to urge the pin 27 downwardly against the inclined surface 22 is materially increased, thus assuring that the seat will promptly return to its normal position when the customer 40 rises and releases the seat.

It will be noted also that rotation of the seat causes the pin to rise slightly within the socket with the result that the lubricant in groove 29 is distributed vertically between the pin and the 45 interior surface of the socket. In this way lubrication is at all times maintained between the pin and the socket. As all of the lubricant is disposed in the socket there is no danger of any lubricant escaping or a customer inadvertently 50 soiling his clothing. The creation of the partial vacuum in the bottom of the socket also tends to effect a distribution of the lubricant over the interior surfaces of the socket.

It will be noted that the present construction 55 does not require the use of springs to assist in the return of the seat to its normal position but instead, relies upon the creation of the partial vacuum to assist the weight of the seat in bringing about an automatic return. The construction 60 also provides for a vertical adjustment of the seat with respect to the pedestal by adding or subtracting collars or spacers 16. These collars may be omitted entirely if desired. The lug 20 and shoulders or stops 17 and 18 are preferably employed but may be omitted whenever 65 it is desired to have a seat which will revolve through 360° rather than 180°.

It will be appreciated that the present construction is very simple and highly durable and that it may be easily manufactured from two castings with a minimum amount of machine work.

Various changes may be made in the details of construction without departing from the spirit or scope of the invention as defined by the appended claims.

I claim:

1. A connection between counter stools and their pedestals comprising means adapted to be attached to the bottom of a counter stool seat and having a pin extending downwardly therefrom, a socket adapted to be inserted in the top 15 of the pedestal and to have the pin inserted therein said pin having a beveled end engageable with complementary surfaces in the bottom of the socket, there being a lubricant-receiving groove formed around the pin above its beveled 20 end, whereby when the seat is turned it will be lifted by the turning of the bottom of the pin relative to the bottom of the socket creating a partial vacuum between the bottom of the pin and the bottom of the socket which will be preserved by the lubricant in the lubricant-receiving groove, the vacuum being effective to cooperate with the weight of the seat in returning the seat to a predetermined normal position with relation 25 to the socket.

2. A self-aligning counter stool comprising a pedestal, a seat, a pin supporting the seat, there being a socket in the pedestal into which the pin extends, said socket having a closed bottom, the bottom surface of the pin and the bottom of the 30 socket presenting opposed complementary surfaces which when the seat is turned from its normal predetermined position cause the seat to be elevated slightly relative to the pedestal and to return to its normal position when the seat is 35 released, there being provision made for maintaining a seal between the pin and the walls of the socket above said complementary surfaces so that when the seat is turned from the predetermined normal position a partial vacuum will 40 be formed in the socket between said surfaces.

3. A connection between counter stools and their pedestals comprising a pin adapted to support the counter stool seat, means for attaching the pin to the counter stool seat so as to extend 45 downwardly therefrom, a socket adapted to be inserted in the top of the pedestal and adapted to have said pin inserted therein, said pin having a beveled lower end engageable with the complementary surfaces in the bottom of the socket, 50 said socket having a closed bottom and means for maintaining a seal between the pin and the walls of the socket above the beveled end on the pin so that when the seat is turned from a predetermined position a partial vacuum will be 55 formed in the socket which is effective to cooperate with the engaging surfaces on the pin and socket in returning the seat to its predetermined 60 normal position.

NILS HERMAN CEDERQUIST.
